DESIGN FOR A BOTTLE

Frank E. Ansell, Brooklyn, N. Y.

Application October 18, 1945, Serial No. 122,942

Term of patent 14 years

(Cl. D58—8)

To all whom it may concern:

Be it known that I, Frank E. Ansell, a citizen of the United States of America, residing at Brooklyn, in the county of Kings and State of New York, have invented a new, original, and ornamental Design for a Bottle, of which the following is a specification, reference being had to the accompanying drawing, forming a part thereof.

In the drawing:

I claim:

The ornamental design for a bottle, as shown.

FRANK E. ANSELL.
